COAXIAL CONNECTOR

Valentino Colussi, Walled Lake, Mich., assignor to The Bendix Corporation, a corporation of Delaware
 Continuation of application Ser. No. 3,963, Jan. 21, 1960.
 This application Sept. 10, 1962, Ser. No. 223,579
 7 Claims. (Cl. 339—89)

This invention pertains to a coaxial cable connector having good electrical characteristics and being easy to assemble and which can be easily disconnected. This is a continuation of my copending application Serial No. 3,963, filed January 21, 1960, entitled "Coaxial Connector," now abandoned.

It is an object of this invention to provide a coaxial cable connector adapted to connect the center conductors and outer conductors of the free ends of two cable segments which have the outer conductors and insulation stripped away from the center conductors, which includes: end caps being internally threaded at one end and having an inwardly extending flange at the other end with an end cap being placed over the outer conductor of each of the free ends flanged end first; a retainer ring adapted to engage the inwardly extending flange of the end caps, being soldered to the outer conductor of each cable end; an externally threaded sleeve containing a Teflon positioning sleeve and a sleeve having spring members at each end for engaging the center conductors; said threaded sleeve being in threaded engagement with each of the end caps which are tightened on the sleeve so that the inwardly extending flanges of the end caps urge the retaining rings toward one another and against the ends of the threaded sleeve, positioning sleeve to firmly hold the connection.

These and other objects and inventions will become more apparent when a preferred embodiment of this invention is considered in connection with the drawings in which:

FIGURE 1 is a cross section of an embodiment of this invention connecting two coaxial cables;

FIGURE 2 is an end view of the connector; and FIGURE 3 is a sectioned view of the spring sleeve which connects the two center conductors.

In FIGURE 1 is shown the free ends of two coaxial cables 20, 20A, having, respectively, center conductors 22, 22A, insulation 24, 24A, and outer conductors 26, 26A. The insulation 24, 24A and outer conductors 26, 26A are stripped away in this embodiment for .100" for an outer conductor diameter of .140". Soldered at 29, 29A to outer conductors 26, 26A, respectively, are rings 28, 28A, which have shoulders 27, 27A, respectively, formed intermediately thereof. Rings 28, 28A are urged together by the inwardly extending flanges 30, 30A, of end caps 32, 32A which are threadedly engaged with an externally threaded sleeve 34, the ends of which are tightened against shoulders 27, 27A.

Located inside sleeve 34 is a Teflon positioning sleeve 36 in which is a spring sleeve 38 having a plurality of fingers 40 at one end and fingers 40A at the other, as shown in FIGURE 3. In the relaxed position the fingers 40, 40A of spring sleeve 38 come together at their outer ends and, therefore, when the center conductors 22, 22A are inserted in the ends of the sleeve 38, the fingers 40, 40A, are separated and exert a spring pressure on the

2

conductor 22. This insures a good electrical connection and serves to clean the conductors as the sleeve slides over the conductor ends. Retainer rings 28, 28A, end caps 30, 30A, and sleeves 34, 38 are preferably of brass material with a .0002" silver plate. Each end cap 30 is provided with wrench slots 31, as seen in FIGURE 2, to assist in tightening of the connector.

Assembly

In assembling the preferred embodiment connector of this invention, the end caps 30, 30A are first placed over the stripped ends of coaxial cables 20, 20A and slid along the outer conductors 26, 26A, so that retaining rings 28, 28A may be placed respectively over outer conductors 26, 26A, and soldered at 29, 29A. Then sleeve 34, containing insulation 36 and spring sleeve 38, is inserted over the inner portion of the retaining ring 28 until the respective sleeve end abuts shoulder 27 of ring 28 with fingers 40 sliding over the center conductor 42. Then the other conductor is inserted into sleeve 34 until the shoulder 27A of retaining ring 28A abuts the other end of sleeve 34, at which time the center conductor 22A will be inserted in the fingers 40A of spring sleeve 38. The end caps 30, 30A are now moved along the outer conductors 26, 26A, threadedly engaged with sleeve 34 and tightened on the sleeve urging the retainer rings 28, 28A toward one another against the ends of sleeve 34 to insure a firm, secure connection.

Although this invention has been disclosed and illustrated with reference to particular applications, the principles involved are susceptible of numerous other applications which will be apparent to persons skilled in the art. The invention is, therefore, to be limited only as indicated by the scope of the appended claims.

Having thus described my invention,

I claim:

1. A connector for connecting the free ends of two coaxial cables having their outer conductor and insulation stripped away to expose a predetermined length of the inner conductor comprising
 two internally threaded end caps,
 one end cap rotatably mounted on one cable,
 the other end cap rotatably mounted on the other cable,
 a first ring being bonded to the outer conductor of
 said one cable,
 a second ring being bonded to the outer conductor of
 said other cable,
 an externally threaded sleeve which is threadedly en-
 gageable with both of said threaded end caps, rigid
 tubular insulating means closely fitting within said
 sleeve intermediate the ends thereof, a double-ended
 socket contact wholly within and supported by said
 sleeve for receiving and electrically contacting the
 exposed lengths of the inner conductors of said
 cables,

first engaging means being connected to one end cap
 for rotatably engaging said first ring,
 second engaging means being connected to the other
 end cap for rotatably engaging said second ring, the
 adjacent ends of
 said rings and cables slidably extending into the ends
 of said sleeve and being urged toward each other
 by said engaging means as said end caps are screwed
 on said sleeve until said inner conductors make elec-

trical contact with said socket contact and said cables are in end-to-end abutment with the ends of said insulating means.

2. The combination comprising a coaxial cable having its inner conductor exposed beyond the end of its outer conductor and the cable insulation therebetween, a tubular metallic casing member, tubular insulating means disposed within said member intermediate the ends thereof, a socket contact mounted wholly within said insulating means and adapted to receive the exposed end of said inner conductor, a metallic ring surrounding and secured to the outer conductor of said cable, said ring terminating flush with the end of said outer conductor of the cable and having a portion slidably telescopically received in one end of said casing member, and a nut cooperably associated with said casing member and ring for holding the ring and cable in telescopic relation with said casing member with the ends of said insulating means and said cable insulation in abutting relation.

3. The combination defined in claim 2, wherein said ring has an external shoulder cooperable with the end of said casing member to limit movement of said ring and cable into the casing member after said inner conductor engages said socket contact.

4. The combination defined in claim 2 further comprising means for limiting axial movement of said insulating means into said casing member toward the other end of the latter.

5. The combination defined in claim 4, wherein said last-named means comprises a second coaxial cable, ring and nut in combination with each other and with the

other end of said casing member in the same manner as said first-named cable, ring and nut are combined with each other and with said one end of the casing member.

6. The combination defined in claim 1, wherein said insulating means is a rigid unitary tube slidably received in said casing member and held therein by said nut in end-to-end abutment with said cable and ring.

7. The combination defined in claim 1, wherein the outer diameter of said socket contact is greater than the diameter of said inner conductor of the cable and the inner diameter of said casing member surrounding said insulating means is greater than the inner diameter of said outer conductor of the cable.

CERTIFICATE OF CORRECTION

Patent No. 3,147,057

September 1, 1964

Valentino Colussi

It is hereby certified that error appears in the above numbered patent requiring correction and that the said Letters Patent should read as corrected below.

Column 2, line 37, begining with "A connector" strike out all to and including "insulating means.", in column 3, line 3, and insert instead the following:

A connector for connecting the free ends of two coaxial cables having their outer conductor and insulation stripped away to expose a predetermined length of the inner conductor comprising
two internally threaded end caps,
one end cap rotatably mounted on one cable,
the other end cap rotatably mounted on the other cable,
a first ring being bonded to the outer conductor of
said one cable,
a second ring being bonded to the outer conductor of
said other cable,
an externally threaded sleeve which is threadedly engageable with both of said threaded end caps,
rigid tubular insulating means closely fitting within
said sleeve intermediate the ends thereof,
a double-ended socket contact wholly within and supported by said sleeve for receiving and electrically contacting the exposed lengths of the inner conductors of said cables,
first engaging means being connected to one end cap for rotatably engaging said first ring,
second engaging means being connected to the other end cap for rotatably engaging said second ring,
the adjacent ends of said rings and cables slidably

3,147,057

} extending into the ends of said sleeve and being urged toward each other by said engaging means as said end caps are screwed on said sleeve until said inner conductors make electrical contact with said socket contact and said cables are in end-to-end abutment with the ends of said insulating means.

column 4, lines 4 and 8, for the claim reference numeral "1", each occurrence, read -- 2 --.

Signed and sealed this 19th day of January 1965.
